[57] CLAIM

The ornamental design for an automatic thermostat control, as shown and described.

DESCRIPTION

FIG. 1 is a front elevational view of an automatic thermostat control showing my new design;

FIG. 2 is a top plan view;

FIG. 3 is a bottom plan view;

FIG. 4 is a rear elevational view;

FIG. 5 is a right side elevational view;

FIG. 6 is a left side elevational view;

FIG. 7 is a front elevational view of the control with the cover open; and

FIG. 8 is a right side elevational view thereof.

The broken line showing of a thermostat in FIG. 1 is for illustrative purposes only and forms no part of the claimed design.
